CONVERSION OF MINERAL OILS

David G. Brandt, Westfield, N. J., assignor to
Cities Service Oil Company, New York, N. Y., a
corporation of Pennsylvania

Application August 16, 1938, Serial No. 225,079

10 Claims. (Cl. 196—11)

This invention relates to a process for cracking or converting hydrocarbons into products suitable motor fuel, and particularly, products boiling within the gasoline range of boiling points.

More particularly, this application relates to improvements in the handling of the conversion products produced in cracking processes in which a substantial proportion of the products are in vapor form. In certain respects, this application contains subject-matter disclosed in pending applications Serial Nos. 720,539 and 158,900, filed by the applicant on April 14, 1934, and August 13, 1937, respectively, now Patents No. 2,189,191, granted February 6, 1940, and No. 2,217,587, granted October 8, 1940. The subject-matter of this application is also an improvement on and includes some of the subject-matter disclosed in application Serial No. 548,062, filed July 1, 1931, the disclosure of which is now in Patent No. 2,198,263, granted April 23, 1940. This application also includes subject-matter disclosed in applicant's Patent No. 2,074,978, granted March 23, 1937, and application Serial No. 104,387, filed October 7, 1936, and now Patent No. 2,168,318, granted August 8, 1939.

The primary object of the present invention is to provide an improved process for the conversion of hydrocarbons, and more particularly for the handling of the high temperature products produced in hydrocarbon conversion operations.

A further object of the invention is to provide an improved process for the conversion of hydrocarbons, and more particularly a process relating to the utilization of the higher boiling constituents of the conversion products in the recovery of certain of the lower boiling constituents.

A further object of the invention is to provide an improved cracking unit particularly adapted for handling practically all stocks available in a small refinery.

In accordance with the disclosure of the applicant's pending application S. N. 158,900 referred to above, the process described and claimed therein, includes the simultaneous heating of a distillate such as butane, and a gas oil distillate, in separate heating zones, heating the "butane" distillate to a substantially higher temperature and pressure than that to which the gas oil is heated, mingling the products of both heating operations, and subjecting the resulting mixture to further heating and conversion conditions of temperature and pressure adapted to cause an interpolymerization of the constituents of the mixture. This polymerization operation may be carried out in a pipe still furnace and an en-

larged digestion chamber. After the mixture has been converted to the desired extent, the products are quickly cooled to a temperature adapted to prevent substantial further reaction and to condense any heavy oil constituents which may be present. The application also discloses the fractionation of the remaining vapors and the return of respectively higher boiling and lower boiling distillate stocks than gasoline, to the respective heating zones for retreatment.

Application Serial No. 720,539 discloses a cracking operation in which high temperature conversion products are introduced into the upper portion of an enlarged vertical reaction chamber and passed downwardly therethrough to the bottom of the chamber from which they are discharged through a funnel-like structure. As the high temperature products enter the funnel, they are suddenly chilled to a temperature below that at which substantial cracking takes place by spraying a relatively heavy oil directly into the vapors, so that there is no substantial formation of coke. The products discharged through the funnel pass into a separating chamber from which vapors are separated from liquid, the liquid being withdrawn into a low pressure concentrator for the production of fuel oil and a concentrator distillate. The vapors from the concentrator are condensed as a single distillate and used as the cooling medium sprayed into the funnel structure. Any excess of this concentrator distillate is brought in contact with the vapors separated out in the separating chamber below the funnel, after the vapors are passed into the lower portion of a fractionating column where they also afterward pass in indirect heat exchange with crude oil charging stock.

Applications Serial No. 548,062 and Serial No. 104,387 disclose a process and apparatus for distillation and stabilization in which the vapors from the dephlegmator of a cracking unit at a pressure of approximately 235 lbs. per square inch gauge are conducted through heat exchangers and a cooler to condense the readily condensable constituents under the pressure of the cracking unit. The resulting condensate is separated from dry gases and then used as an absorption medium in an absorber to take up hydrocarbon gases such as obtained from a gas gathering system. The resulting condensate and gases are then passed through the heat exchangers referred to and into the mid-portion of a rectifying column which is utilized for removing the lower gases such as ethane and methane. The liquid collected in the base of the

rectifying column is sent to a second similar column for the removal of C₃ hydrocarbons overhead, after which the liquid from the base of this second column is conducted to a third column which produces C₄ hydrocarbons overhead and a stabilized bottoms product of the desired vapor pressure or content of C₄ hydrocarbons. Heated reboilers are used for each of the rectifying columns. Overhead reflux is supplied to each of the columns from condensates of overhead vapors. The first column may be operated under a considerably higher pressure than that of the cracking unit, for example, at approximately 400 lbs. per square inch. The second column is operated at a pressure of approximately 210 lbs. per square inch, while the third column may be operated at approximately 60 lbs. per square inch.

In accordance with the features and objects of the present invention, the improvements comprise a method for handling converted oil products from any type of conversion apparatus. The method particularly comprises the steps of first eliminating the very heavy constituents such as fuel oil not desired for further processing, from the conversion products, using the gasoline and cycle oils contained in the remainder of the conversion products for condensing and absorbing all of the products except the relatively "dry" gases such as hydrogen and methane, and fractionating the condensed conversion products into marketable fractions, and fractions to be returned and reprocessed in the conversion apparatus.

Other features, objects and advantages of the process and apparatus of the present invention, will be apparent to those skilled in the art from the following more detailed description taken in connection with the accompanying drawing, in which:

The single figure is a conventional elevational diagram of an apparatus particularly adapted for carrying out the improvements of the present invention.

The particular improvements of the present invention may be applied to the conversion of petroleum oils as carried out in any of the usual tube or tube and chamber cracking processes. The highly heated conversion products from a pipe still furnace or furnaces, for example such as described in application Serial No. 158,900 are conducted into the apparatus shown in the drawing while at a high temperature through a line 2 and introduced, preferably at a tangent, into the upper portion of an enlarged (broken) reaction chamber 4 comprising the upper portion of a vertical tower. The highly heated partially cracked products introduced into the chamber 4 flow downwardly through the chamber and pass through a funnel 6 which extends into a cooling chamber 8. The liquid portion of the conversion products flows to the bottom of the chamber 8 while the vapors pass around the lower end of the funnel and are subjected to intimate contact with a cooling liquid preferably a distillate, introduced through a spray ring 10. Sufficient oil is introduced through this spray ring to quickly cool the vapor products to a temperature at which any fuel oil type constituents which may be in the vapors will be condensed.

All of the liquid material in the chamber 8 flows into the narrow bottom section of the chamber and is discharged through a float valve controlled line 12 into a concentrator 14 in which all of the constituents not desired in the fuel oil

is vaporized by a substantial reduction in pressure which occurs in the line 12. The fuel oil constituents remaining unvaporized in the still 16 are conducted through a line 18 and discharged from the system by means of a pump mounted therein and passed through a cooler.

The vapors formed in the concentrator 14 will comprise gas oil constituents as well as lower boiling hydrocarbons which may be dissolved in the liquid oil in the bottom of the chamber 8 under the pressure and temperature conditions maintained therein. These vapors are conducted from the still 14 through a vapor line 18, a condenser 20 and a line 22, into a receiver and gas separator 24. Any uncondensed gases are discharged from the receiver 24 through an automatic pressure valve controlled line 26. The distillate collected in the bottom of the receiver 24 is utilized for effecting the cooling of the cracked products from the chamber 4 and is therefore withdrawn through a line 28 and forced by means of a pump mounted therein into the spray ring 10. A part or all of the cooling may be effected by introducing cool distillate at a tangent into the cracked products entering the funnel 6 from a branch line 29. Any excess of this distillate over that required for effecting the cooling of the cracked products is discharged through a valved line 30. The vapors now remaining uncondensed in the chamber 8 and which have been cooled by oil sprayed from the ring 10, now include a substantial proportion of constituents boiling above the boiling point of gasoline as well as hydrocarbons boiling below the initial boiling point of gasoline, and uncondensable gases such as hydrogen, methane, ethane, ethylene, etc.

These vapors are discharged from the upper part of the chamber 8 through a line 32 in which is mounted a heat exchanger for partially cooling the vapors preferably by heat exchange with oil charging stock or with feed stock for the pipe still heater or heaters used in connection with the process. The products in the line 32 are used as a heating medium for heating the lower portion of a series of fractionating towers and accordingly, the products are first conducted through a heater 34 mounted in the lower portion of a fractionating tower 36, then into a valved line 38 and a connecting line 40 which discharges into a separator-stripper 42 where any condensate, preferably gas oil constituents, are separated from the remainder of the vapors which are passed from the chamber 42 through a line 44 back into the line 38 beyond the valve as shown.

The portion of the oil constituents in the line 38 may be conducted directly through the valve therein without being passed to the separator 42, but the products in the later portion of this line are conducted through a heater 46 mounted in the lower portion of a fractionating tower 48 to maintain the desired temperature therein. The products introduced into the heater 46 are discharged through a line 50 and conducted into a further heater 52 mounted in the lower portion of a fractionating tower 54.

The passing of the conversion products through the heaters 34, 46 and 52, effects a substantial cooling and condensation of the products, and the mixture introduced into the heater 52 is discharged through a line 56 and passed through a heat exchanger 58, a line 60, a cooler 62 mounted in line 60 and finally into the lower portion of a separator-absorber 64. The excess of the concentrator distillate produced in the operation,

and discharged through the line 30, is conducted into the line 56 and mingled with the products therein which pass to the absorber 64. Sufficient final cooling is applied in the cooler 62 to effect the condensation of all of the constituents of the conversion products except for the gaseous constituents referred to above.

A pressure of from 175 to 250 lbs. per square inch may be maintained in the absorber 64 and a back pressure is preferably maintained from this absorber through the previously described equipment including the chambers 4 and 8. The heavy condensate collected in the stripper 42 is brought into intimate contact with gas such as methane, to remove the low boiling constituents which pass with the vapors through the line 44. The stripped heavy condensate is withdrawn from stripper 42, passed through a cooler into a line 66 and then passed into the upper part of the absorber 64 where it is brought in contact with the gases rising therein. The high pressure in the absorber 64, together with the intimate contact of the heavy oil, prevents the removal of C₃ and C₄ hydrocarbons with the lower gases which are discharged through an automatic pressure valve controlled line 68. The absorber 64 is preferably provided with means for intimately contacting the heavy condensate, cooled to any desired extent, with the gases separated out in the bottom of the absorber. Oil from an outside source or from the line 30 may supply all or a part of the oil for absorber 64.

The condensate collected in the base of the absorber 64 may be processed in various ways for the recovery of the desired gasoline constituents from the higher boiling and lower boiling hydrocarbons. However, the preferred method of handling this condensate mixture will be described in connection with the use of towers 36, 43 and 54. Accordingly, the condensate mixture is withdrawn from the absorber 64 through a line 64 and forced by means of a pump mounted therein at a pressure of about 500 lbs. per square inch through the heat exchanger 58 and then through a line 72 into the midportion of the tower 54 which is utilized for the purpose of removing excessively volatile constituents comprising C₁ hydrocarbons and lower gases which may be absorbed in the mixture.

The tower 54 is of the usual bubbler plate construction and is maintained under a pressure of about 500 lbs. per square inch with a bottom temperature of approximately 375° F. The vapors evolved in the tower 54 pass upwardly therethrough in counter-current contact with reflux condensate and uncondensed vapors and gases passing overhead through a cooler 74 which returns reflux condensate to the top of the tower 54. The uncondensed vapors and gases including C₂ and lower gases as well as some C₃ hydrocarbons pass from the cooler 74 through a line 76 into the lower portion of an absorber or scrubber 78 and pass upwardly therethrough counter-current to a heavy oil which absorbs the C₃ hydrocarbons from the gases. The unabsorbed gases are discharged from the absorber 78 through an automatic pressure valve controlled line 80, which maintains the back pressure on tower 54. The heavy oil brought in contact with the gases in the absorber 78 may be introduced from an outside source, but it is preferably taken from the line 66 and passed through a line 82 by means of a pump mounted therein into the upper part of the absorber 78. Concentrator distillate from the line 30 may be passed through a line 83 and line

82 into the absorber 78 as the heavy oil. The relatively heavy oil containing the absorbed C₃ hydrocarbons (as well as some C₂ hydrocarbons) flows from the bottom of the absorber 78 through a line 84 into the line 72 and then into the mid-portion of the tower 54. The temperature of the high boiling condensate passed through the line 82 will be the same as that passed through the line 68 into absorber 64, but the pressure in the absorber 78 will be approximately 500 lbs. or considerably higher, so that any of the C₃ hydrocarbons will be readily absorbed and returned to the mixture in the tower 54.

The condensate mixture produced from the vapors discharged through the line 32 and now free of undesired gaseous constituents, is conducted from the bottom of tower 54 through an automatic float valve controlled line 86 into the mid-portion of the fractionating tower 43 which is used for the purpose of separating from the condensate the C₃, and a substantial proportion of the C₄ hydrocarbons. These constituents are vaporized in the tower 43 which is operated at a pressure of about 200 lbs. per square inch and at a bottom temperature of about 400° F. The proportion of C₄ hydrocarbons removed in the mixture is controlled so that the final gasoline product will contain the desired proportion to give the proper vapor pressure. The vapors formed in the tower 43 are conducted overhead through a vapor line 88, condensed and collected in a receiver 90. A portion of the condensate may be passed from the receiver 90 into the top of the tower 43 to provide the necessary reflux ratio, and any uncondensable gas is discharged from the receiver through an automatic pressure valve controlled gas line as shown. The mixture of C₃ and C₄ hydrocarbons collected in the receiver 90 and discharged therefrom through a valved line 92, may be used directly as a charging stock for the conversion operation, in a manner similar to that disclosed in said pending application.

The condensate passing to the bottom of the tower 43 now comprises the desired gasoline constituents and heavier hydrocarbons, but is free of the gases and lower boiling constituents. This condensate is conducted from the bottom of the tower 43 through an automatic float valve controlled line 94 and passed into the mid-portion of the final tower 36 for the fractional separation of the gasoline from the heavier constituents of the mixture. The tower 36 is operated at a pressure of about 30 lbs. per square inch and at a bottom temperature of about 500° F. which is sufficient to vaporize and remove all of the gasoline constituents overhead from the tower. The gasoline in the vapor form is discharged from the tower 36 through a vapor line 96, condensed and collected in a receiver 98. Any uncondensed gases are discharged from the receiver 98 through an automatic pressure valve controlled line, and a portion of the gasoline is returned from the receiver to the top of the tower 36 to maintain the required reflux ratio for the fractionating operation. The finished gasoline product free of higher and lower boiling constituents produced in the conversion operation is discharged from the receiver 98 through a line 100 and cooled by means of a cooler mounted therein.

The back pressure maintained in the receiver 98 (as well as that in 90) is preferably controlled automatically by controlling the condensation of the vapors conducted from the tower 36 through the line 96. As shown in the drawing the cooling water for the condenser in the line 96 is auto-

matically controlled by the pressure in the receiver 98 so that the amount of cooling water supplied will be increased if the pressure rises above a predetermined point set for operating the water supply valve. Although the normally gaseous hydrocarbons will have been removed in previous elements of the apparatus, enough will still remain along with C₄ hydrocarbons for maintaining the back pressure from the receiver 98.

The high boiling constituents introduced into the tower 36 include those immediately higher boiling than the gasoline, as well as relatively heavy gas oil constituents. While these products may be collected at the bottom of the tower as a single fraction and discharged through an automatic float valve controlled line 102, the fractionation is preferably so conducted that a side stream suitable for furnace oil is withdrawn. Accordingly, provision is made for withdrawing such a side stream from one or more mid-points in the tower above the inlet 94, as shown, into a line 106, by which it is passed into a stripping column 108. This side stream will comprise a fraction immediately higher boiling than the gasoline product and be suitable as a light furnace oil. The side stream is stripped of light constituents such as those boiling within the gasoline range, by introducing gas or steam into the bottom of the stripper 108. The removed vapors and stripping medium are passed into the tower 36 above the point of withdrawal of the side stream. The stripped fraction is discharged through a line 110 and passed through a cooler 112 and discharged through a valved line 114. A portion of the cooled furnace oil may be passed from the line 114 through a line 116, by a pump therein, into the absorber 64 to supply all or a part of the absorption oil used therein.

In controlling the temperatures maintained in the bottom of the towers 36, 48 and 54 provision is made for using valved by-pass lines between the inlet and outlet lines for these heaters as shown in the drawing. It will be noted that the pressure is reduced successively through the towers from left to right and that considerable vaporization will be effected because of this pressure reduction. The high boiling condensate, which may be regarded as a relatively heavy gas oil, discharged from tower 36 through the line 102, may be returned to the heater or heaters of the conversion unit and resubjected to cracking conditions for example, in the manner described in said pending application.

The process as described above in connection with the conversion unit shown in the drawing has several distinguishing features which contribute to the economy and ease of handling the converted materials. For example, it will be noted that while normally gaseous conversion stocks are produced, there is no point in the system where it is necessary to pump or compress gases. The use of the separator 64 eliminates a very substantial proportion by volume of the vapor mixtures which are normally handled in the fractionating equipment of present day cracking units. The light hydrocarbons recovered in the system for retreatment, are recovered as liquids without the necessity of compressing gases.

One of the important features of the process of the present invention is the retention of high boiling point hydrocarbons in the mixture of conversion products, so that their presence is utilized in the handling of the low boiling constituents particularly normally gaseous hydrocarbons. In the operation, the excessively heavy, fuel oil type,

hydrocarbons are separated from the conversion products in the chamber 8. The next step comprises the elimination of the excessively volatile or gaseous constituents. Finally, the desired gasoline range hydrocarbons are recovered from the mixture which includes lower and higher boiling hydrocarbons. This mixture may be handled in the manner described in connection with the drawing or by various other methods to separately recover the gasoline range constituents, the lower boiling hydrocarbons, and the higher boiling hydrocarbons.

As a further example, the mixture containing the gasoline and adjacent lower and higher boiling hydrocarbons (after being freed of excessively heavy and light constituents) may be separated into several fractions, after which the constituents lower boiling than gasoline may be fractionated into more or less individual classes of hydrocarbons, such as C₃ and C₄ groups, each of which may be separately polymerized or utilized for various purposes in the industries.

The process of the present invention may be applied to the handling of a mixture of conversion products regardless of the type of cracking operation used for their production, whether liquid phase, vapor phase, or a mixed liquid and vapor cracking operation. In handling the products from a liquid phase operation, the excessively light gases are preferably first eliminated from the mixture, after which the next lighter constituents may be successively removed by fractional distillation. On the other hand, the products from a liquid phase conversion operation may be handled by first eliminating the excessively light gases and then vaporizing the greater part of the mixture to eliminate the fuel oil constituents, after which the remainder of the conversion products may be fractionated by fractional condensation or by condensing the whole of the remainder and fractionating it by fractional distillation in the manner specifically described above in connection with the apparatus shown in the drawing.

From the foregoing description of the improved process and apparatus of the present invention, it is apparent that the central features of the process may be applied to various types of cracking processes and that many modifications may be made in the apparatus and the operations carried out without departing from the spirit and scope of the invention, as defined by the accompanying claims.

Certain subject-matter disclosed herein is disclosed and claimed in applicant's application Serial No. 371,929, filed December 27th, 1940.

Having thus described the invention in its preferred form, what is claimed as new is:

1. In the conversion of hydrocarbons into anti-knock gasoline in which a vapor mixture comprising the conversion products is produced in the conversion operation, said mixture containing the constituents of the desired gasoline product as well as higher and lower boiling readily condensable constituents and uncondensable gases, the improvement which comprises subjecting the vapor mixture to cooling and condensing conditions to produce a relatively high boiling condensate therefrom of higher boiling point than pressure distillate, subjecting the remaining uncondensed vapors and gases to further condensing conditions to condense all of the remaining readily condensable constituents, passing the resulting condensate and uncondensable gases into the lower portion of a scrubbing tower in which

the uncondensable gases are separated out and passed upwardly through the tower, passing the said relatively high boiling condensate into the upper part of said tower and passing it downwardly therethrough in intimate contact with the gases rising through the tower and then into the lower portion of said tower, discharging the unabsorbed gases from the top of the tower and fractionating the combined condensates including said high boiling point condensate and absorbed gaseous constituents collected in the bottom of the tower to separately recover the desired gasoline product and lower boiling point condensable hydrocarbons therefrom.

2. The process as defined by claim 1 in which a relatively high superatmospheric pressure is maintained in said tower and in which the condensing and scrubbing operations are conducted under such conditions that substantially no C₃ or higher hydrocarbons are discharged from the top of the tower.

3. The process as defined by claim 1 in which the condensate mixture recovered in the bottom of said tower is subjected to a rectification operation at a pressure substantially higher than that maintained in said tower to eliminate any dissolved hydrocarbons below C₃.

4. The process of handling the conversion products of a thermal conversion operation in which such products include hydrocarbons within the range of fuel oil through uncondensable gases of the type usually produced in thermal conversion operations, which comprises eliminating the fuel oil constituents from the mixture of conversion products, thereafter condensing all of the readily condensable constituents including C₃ hydrocarbons as a single condensate and fractionally distilling and rectifying the resulting condensate in a series of fractionating towers, said condensing operation including the passage of the fuel oil-free conversion products initially in vapor form through the lower portion of each of said series of fractionating towers in indirect heat exchange with hydrocarbon constituents in the base of said towers whereby heat is supplied to said towers and said vapors are cooled and progressively condensed, separating gases including C₂ hydrocarbons not readily condensable from said condensate, separating a high boiling condensate in the progressive condensing operation and passing it in intimate contact with said separated gases, mixing the resulting high boiling condensate containing absorbed constituents with the condensate separated from said gases, passing the resulting condensate mixture including C₃ and some absorbed C₂ hydrocarbons into the first of said fractionating towers and therein rectifying the mixture under conditions adapted to remove overhead substantially only C₃ and lower hydrocarbons, passing the remainder of the condensate from said first tower into the second tower of said series and rectifying the same therein to produce overhead a C₃ hydrocarbon condensate, passing condensate from said second tower to the third tower and therein rectifying the condensate to take overhead a desired gasoline boiling product, and recovering from said third tower an oil fraction of higher boiling point than gasoline suitable as a charging stock for the conversion operation.

5. In the conversion of hydrocarbons into anti-knock gasoline in which a mixture comprising the conversion products is produced in the conversion operation, said mixture containing the constituents of the desired gasoline product as well as higher and lower boiling readily condens-

able constituents, uncondensable gases, and fuel oil type hydrocarbons, the improvement which comprises eliminating fuel oil constituents from the mixture, thereafter subjecting the remainder of the mixture to a condensing operation in which the readily condensable constituents are condensed to produce a high boiling distillate and a final condensate, passing the final condensate and normally uncondensable gases into an absorber and passing the gases in intimate contact with an absorption medium therein under conditions adapted to absorb substantially all of the C₃ hydrocarbons, mixing the resulting rich absorption medium with the condensate introduced into the absorber and passing the resulting mixture into a high pressure rectifying tower in which the mixture is rectified under conditions adapted to produce a bottoms product substantially free of C₂ and lower boiling constituents, passing a vapor fraction discharged from the upper part of the rectifying tower and comprising C₂ and lower boiling constituents as well as some C₃ hydrocarbon into a second absorber in intimate contact with an absorption medium comprising said high boiling distillate adapted to absorb substantially all of the C₃ hydrocarbon, and passing the rich absorption medium from said second absorber into said rectifying tower to be fractionated therein along with the condensate mixture introduced therewith.

6. The improvement in the conversion of hydrocarbons as defined by claim 1 in which the condensate mixture recovered in the bottom of said scrubbing tower is passed into a high pressure fractionating tower and therein subjected to rectifying conditions adapted to produce a bottoms product substantially free of C₂ and lower boiling constituents, and in which a vapor fraction discharged from the top of the fractionating tower and comprising C₂ and lower boiling constituents as well as some C₃ hydrocarbon is passed into a second scrubbing tower in intimate contact with an absorption medium adapted to absorb the C₃ hydrocarbon, and passing the rich absorption medium from the second scrubbing tower into said fractionating tower to be fractionated therein.

7. In the conversion of hydrocarbons into anti-knock gasoline in which a mixture comprising the conversion products is produced in the conversion operation, said mixture containing the constituents of the desired gasoline product as well as higher and lower boiling readily condensable constituents, uncondensable gases, and fuel oil type hydrocarbons, the improvement which comprises separating the fuel oil constituents from the mixture at a substantial superatmospheric pressure, condensing the remainder of the readily condensable constituents including C₃ hydrocarbons as a single condensate, separating the resulting condensate from uncondensable gases, passing all of the condensate into a fractionating tower and therein rectifying the condensate mixture to remove overhead any C₂ and lower hydrocarbons which may have been contained in the condensate mixture, distilling the separated fuel oil constituents at reduced pressure to produce a high boiling distillate, passing said high boiling distillate in intimate contact with the hydrocarbons removed overhead from said fractionating tower for the absorption of any C₃ and higher hydrocarbons contained therein, and mixing the resulting high boiling distillate and absorbed constituents with the condensate mixture prior to

subjecting it to rectification in said fractionating tower.

8. In the conversion of hydrocarbons into anti-knock gasoline in which a vapor mixture comprising the conversion products is produced in the conversion operation, said mixture containing the constituents of the desired gasoline product as well as higher and lower boiling readily condensable constituents and light hydrocarbon gases, the improvement which comprises subjecting the vapor mixture to cooling and condensing conditions to condense all of the readily condensable constituents, passing the resulting condensate including retained light hydrocarbon gases into the mid-portion of a high pressure fractionating tower in which the condensate is subjected to rectification under conditions adapted to produce a liquid bottoms product substantially free of C₂ and lower boiling hydrocarbon gases, cooling the vapors at the top of the fractionating tower to provide a low boiling reflux liquid for the top of the tower, passing the said reflux liquid counter-current to the vapors and gases in the upper portion of the tower in the absence of introduced high boiling constituents to aid in the

rectification in the tower above the point of introduction of said condensate, passing a vapor fraction discharged from the upper part of the tower and comprising C₂ and lower boiling hydrocarbon gases as well as some C₃ hydrocarbon into an absorber separate from said tower, passing the said vapor fraction in said absorber in intimate contact with an absorption medium adapted to recover substantially all of the C₃ hydrocarbon introduced into the absorber, and passing the rich absorption medium from said absorber into the mid-portion of said high pressure fractionating tower and subjecting it to rectification therein along with said condensate introduced into said tower.

9. In the conversion of hydrocarbons as defined by claim 8 in which the condensate is rectified in said fractionating tower at a pressure of at least about 500 lbs. per square inch.

10. In the conversion of hydrocarbons as defined by claim 8 in which the pressure maintained in said absorber is substantially equal to that maintained in said fractionating tower.
